WINDING MACHINE

Edward F. Parks, Providence, R. I., assignor to
Universal Winding Company, Boston, Mass., a
corporation of Massachusetts

Application September 19, 1931, Serial No. 563,865

10 Claims. (Cl. 242--27)

This invention relates to winding machines for winding yarn, thread and other strand materials to produce cops, bobbins, pirns and similar forms of packages wherein the yarn is laid in overlying courses on a conical chase with the cop assuming a generally cylindrical form with a tapered or pointed nose end from which the yarn delivers in unwinding. In the following specification and claims the term "cop" is used in a general sense to designate a package of yarn of the type indicated and the term "yarn" is also employed in a broad sense as applying to all kinds of strand materials.

One object of the invention is to provide a gang winding machine having a plurality of winding units operated from a common driving means and adapted to be individually detached and removed from the machine for repair or replacement without disturbing the operation of the other units.

Another object of the invention is to provide a winding machine of the type specified having a minimum number of operating elements to reduce its mechanism to the utmost simplicity, and proof against derangement and durable in use over long periods.

Further objects of the improvement are set forth in the following specification which describes a preferred form of construction of the invention, by way of example, as illustrated by the accompanying drawings. In the drawings:

Fig. 1 is a side elevation of one unit of the present improved winding machine shown with a portion of its frame or supporting casing in vertical sectional view;

Fig. 2 is a plan view of the operating mechanism of the winding unit as constructed in accordance with the present invention;

Fig. 3 is a development view of the grooved rim of the cam which operates with a variable traverse motion; and

Fig. 4 is a view of one form of cop or pirn produced on the machine.

Referring to the present drawings, the improved winding mechanism is preferably constructed in the form of a unit which may be applied in multiple to a horizontal frame or casing to constitute a gang machine having any desired number of winding-spindles. As illustrated in Fig. 1 of the drawings, the main frame of the machine comprises a suitable number of legs or standards 2 surmounted by a horizontal bed or casing 3 having longitudinally-extending side-rails 4 in the shape of inverted troughs or box-like casings. The side-rails 4 are preferably

made separate from each other and joined together at their opposite ends by means of cross-members or end-plates 8 held by bolts 9. Each cross-member 8 has step portions 5 resting on overhanging ledges 6 at the sides of the legs 2 and fastened thereto by means of bolts 7. A sheet-metal cover 13 rests on the crowned upper edges of the end-members 8 to enclose the space between the side-rails 4.

The operating-mechanism for each winding unit is assembled on a frame-member or bracket 10 which is attached to the inner lateral wall of the box-like housing or side-rail 4 of the main frame 3 in such manner that any unit may be removed from the gang machine without disturbing its neighboring units or interfering with the operation thereof. This provides for the removal of any one or more units for repair or replacement of their parts, and their reassembling on the main frame, without knocking down the whole machine to render the other units inoperative.

The bracket 10 has a vertical plate-portion 11 adapted to be bolted to the side of the lateral wall of the hollow side-rail or casing 3 by means of bolts 12, see Fig. 2 of the drawings. Projecting laterally from the plate 11 is a semi-cylindrical shell 14 provided with a hub 15 at its outer end, in which is held a ball-bearing for the winding-spindle to be later described. The bracket 10 also embodies a similar hub 16 at the inner end of the shell 14 which is bored to receive a ball-bearing corresponding to that in the outer hub 15. As shown in Fig. 2, the ball-bearings may comprise outer annular races 17 held in the bores of the hubs 15 and 16 to co-operate with inner races 18 secured fast on a horizontal shaft 20 extending axially of the hubs 15 and 16. A series of balls 21 are disposed between the races 17 and 18 to provide anti-friction journals for the shaft 20.

The shaft 20 carries a flanged belt-pulley 22 arranged between its journals and suitably keyed or secured rotatively to the shaft by means of a set-screw 23 illustrated in Fig. 2. The shaft 20 is provided with an enlarged extension 24 at its outer end to which the winding-spindle, designated 25, is secured. As herein illustrated, the winding-spindle 25 is of tapered form to adapt it to receive the tapering quill or paper tube π on which the cop is wound, its rearward end being formed with an enlarged shank 26 inserted in a bore 27 in the end of the shaft extension 24 and held in place by a threaded connection at 28.

Fast on the inner end of the shaft 20 is a pinion 30 which meshes with a larger spur gear 31 journaled on a stud 32 carried at the end of a pivoted

- arm 33. The arm 33 is slotted to receive a bolt 34 screwed into a boss on the plate 11. Fast with the gear 31 is a pinion 35 arranged with its teeth meshing with a larger gear 36 which drives the 5 traverse-cam 40 to be later described. The arm 33 is adjustable on the bolt 34 to provide for the substitution of different gears for the "change" gears 31, 35, whereby to alter the speed ratio between the winding-spindle and traverse-cam.
- 10 The gear 36 has its hub 37 connected with the hub 39 of the cam 40, both the gear and cam being journaled on a headed stud-shaft 41 secured in a boss 42 on the plate 11 by means of a set-screw 43.
- 15 The shaft 20 of the winding unit may be driven from any suitable source of power through the means of a belt passing across the periphery of the driving-pulley 22. Preferably the whole series of winding units is driven from one belt extending longitudinally through the hollow rail or housing 4 in contact with the lower peripheries of the series of driving-pulleys 22. The driving-belt, indicated at 48 in the drawings, may be arranged in the manner as illustrated in U. S. Letters Patent No. 1,950,855, issued March 13, 1934 to Everett C. Lewis. As therein shown the belt passes over idlers at either end of the machine and is connected to a pulley on a line shaft or directly with an electric motor to furnish power 20 to drive the machine. Suitable means are provided for manipulating the belt to start and stop the machine, but these mechanisms are not herein shown and described as they are not related to the present invention.
- 25 The cam 40 is constructed with arms 44 radiating from the hub 39 to support its generally cylindrical rim 45. The inner end of the cam-hub 39 is reduced in diameter and inserted into the bore of the hub 37 of the gear 36 being keyed thereto with a set-screw 46 holding the parts rotatively connected.
- 30 The rim 45 of the cam 40 has a generally zig-zag shape as illustrated in the development view, Fig. 3, being formed with a slot or groove 47 following the contour of the rim. Referring to Fig. 3, which shows a development of the rim of the cam and its groove 47, the groove comprises six oppositely-inclined courses or leads coextensive with the circumference of the cam. This gives the groove an undulatory course first in one direction and then in the opposite direction with the reversing portions of the groove located at points at either side of a medial plane extending at right-angles to the axis of the cam. In the 35 diagram of Fig. 3 the dot-and-dash line *a—a* intersects the center of the groove at the extreme ends of the courses at one side of the cam, while the three parallel dot-and-dash lines *b—b*, *c—c* and *d—d* represent the opposite extremes of throw of the cam in accordance with each course of its zigzag or undulating trackway. It will be observed by reference to Fig. 3 that the distance *e* between the extremes of throw of the cam at the point designated is of the maximum, while at the 40 next point the extent of the throw is slightly less as represented at *f* and, again, for the last course the extent of throw is still less as represented at *g*. Beyond this point the throw of the cam is increased again to the maximum as represented at *e*.
- 45 In the present form of construction the arrangement of the thread-guide, its reciprocating traverse-bar and the means for feeding the guide outwardly along the winding-spindle during the 45 longitudinal growth in the bobbin are constituted

and arranged substantially as shown in prior U. S. Letters Patent No. 940,489 of November 16, 1909 and No. 945,880 of January 11, 1910. The reciprocating traverse-bar on which the thread-guide 20 is carried is constructed in two sections 51 and 52 connected by a pin-and-slot joint at 53. The main section 51 of the traverse-bar is slidably mounted in a quill-like sleeve or bushing 54 projecting from the side of the bracket 10 through openings in the opposite walls of the casing 3. The inner end of the sleeve 54 is fluted or knurled and driven through a bore in the plate 11 to fixedly secure it in connection therewith. An arm 55 formed integral with the bracket 10 extends rearwardly therefrom and is provided at its end with a bearing 56 in which is held a sleeve or bushing 57 for slidably supporting the traverse-bar section 51 at this end.

50 A slide or crosshead 60 is secured fast on the traverse-bar section 51 between the ends of the sleeves or bushings 54 and 57, a set-screw 61 passing through the side of the slide to clamp it to the bar as shown in Figs. 1 and 2. The crosshead 55 is provided at its top with a forked extension 62 straddling a horizontal rod 63 held at one end in a hole in the plate 11 and at its opposite end in an extension 64 of the outer bearing 56. The rod 63 is secured in place by a set-screw 65 shown in Fig. 1. The crosshead 60 carries a stud or pin 66 on which is journaled a bowl or roller 67 engaging the groove 47 in the rim 45 of the cam 40. Through this latter connection the traverse-bar section 51 is reciprocated in its bearings to impart traversing motion to the thread-guide 50 carried on its outer extension 52.

55 The section 52 of the traverse-bar has its outer end slidable in an outboard bearing 69 supported from an outrigger or bracket 70 attached to the forward side of the rail or casing 4. The bearing for the outer end of the traverse-bar section 52 is swiveled in the manner shown in Patent No. 945,880, above referred to, so that the inner end of the bar may swing inwardly toward the winding-spindle 25 for a purpose as later explained; the pin-and-slot connection between the two sections 51 and 52 providing for this displacement of the outer bar section 52.

60 The thread-guide 50 comprises a guide proper consisting in a grooved porcelain member, designated 70, carried at the end of a bifurcated holder 71. The arms of the thread-guide holder 71 are hingedly supported on the bar-section 52 by means of bearings 72, and between the bearings is a sleeve-nut 74 arranged to engage partial screw-threads on the side of the bar. The nut 74 carries a disk-like contact-wheel 75 adapted to make peripheral contact with the layers of winding as they are disposed on the cop, whereby to turn the sleeve-nut 74 to gradually advance the thread-guide 50 outwardly along the axis of the winding-spindle 25.

65 At the start of the winding the first layers or courses of turns of the yarn are laid directly on the surface of the cop-tube *x* and the contact-wheel 75 is displaced inwardly toward the spindle to effect the contact between its periphery and the winding. This is accomplished by swinging the traverse-bar section 52 inwardly at an inclination to its normal plane. The means for displacing the contact-wheel 75 in the manner 70 noted consists in a former-arm 76 attached to the outer end of the traverse-bar section 51 and having an inclined cam-face 77 which engages an arm or finger 78 on the thread-guide holder 71. When the thread-guide is slid back along the bar- 75

section 52, at the start of the winding, the finger 78 will bear against the cam-face 77 of the former 76 to swing the bar-section 52 inwardly to bring the periphery of the contact-wheel 75 close to the surface of the cop-tube x on which the windings are deposited. As the guide feeds outwardly along the traverse-bar section 52 a gradual recession of the contact-wheel 75 with respect to the winding-spindle 25 takes place as the finger 78 slides down the incline 77 on the former 76, this action being to accommodate the growth in the winding at the heel of the cop. The construction and method of the operation of this part of the present machine is described in detail and more fully explained in the prior patents above referred to.

The method of operation of the present improved winding mechanism is as next explained. A paper cop-tube or quill x is placed on the spindle 25 and the thread or yarn y led through the groove in the thread-guide 70 and its end secured to the spindle in any suitable manner. It will be understood that previous to starting the winding operation the thread-guide 50 is set back at the butt end of the spindle 25 by releasing the sleeve-nut 74 from the threads on the bar-section 52 to allow the guide-holder 71 to be slid along the bar.

Power is applied to drive the operating mechanism of the individual winding units by causing the belt 48 to be pressed against the driving-pulleys 22 in the manner as explained in the pending application for patent previously referred to. As the pulley 22 is driven from the belt 48 the shaft 20 is rotated thereby and, through the train of gearing 31, 35 and 36, the cam 40 is driven in a clockwise direction. At each rotation of the cam 40 the roll 67 traverses its groove 47 and the crosshead 60 is thereby reciprocated back and forth along its guide-rail or rod 63. The crosshead 60 is fast on the traverse-bar section 51 and thereby a reciprocating motion is transmitted to the latter and to the section 52 of the bar connected therewith. The reciprocation of the traverse-bar causes an oscillating traversing motion of the thread-guide 50 whereby the yarn y is directed back and forth on the cop-tube x to deposit it in a series of crossing helices forming courses which build up the layers of the cop.

The cam 40 acts to impart motion to the thread-guide 50 with a variable extent of traverse. Referring to Fig. 3 of the drawings, as the cam turns in the direction indicated in this view the roller 67 on the crosshead 60 will travel from right to left in the groove 47. Assuming that the roll is at the right-hand end of the cam-groove 47, as shown in Fig. 3, the initial traverse of the guide 50 as the roll passes through the first inclined portion of the cam groove will be of maximum extent as indicated at e . The direction of traverse of the thread-guide is reversed as the roll 67 moves back in the oppositely inclined portion of the cam groove 47 and at this point the extent of movement of the guide will be slightly less than during its initial traverse as indicated at f in Fig. 3. As the direction of traverse is again reversed by the roll traveling in the next succeeding course of cam groove 47 the extent of traverse remains the same as indicated at f , but at its next reversal the guide will have a still less extent of traverse as indicated at g in Fig. 3. Once again the guide is traversed to the same extent, but at its next reversal the length of trav-

erse is increased to the maximum as indicated at e .

As the winding proceeds the yarn is laid in series of courses in the manner as above explained and after a sufficient number of turns have been deposited in one location to build up a predetermined thickness of the layers of windings the thread-guide is advanced outwardly along the winding-spindle. This progressive advance or feeding of the guide 50 axially of the winding-spindle is accomplished by the peripheral engagement of the contact-wheel 75 with the surface of the wound layers and the feed is intermittent or with a step-by-step advance.

The winding is continued until the cop reaches the desired length, at which time the operation of the machine is arrested by releasing the driving-belt 48 from contact with the pulley 22.

The present improved winding mechanism is compacted within a minimum space and assembled and mounted as a complete unit which may be removed from the gang machine for repair or replacement of its parts without disturbing the other units. Each winding unit is detachable from the machine frame by merely removing the bolts 12 and withdrawing the bearing-casing 14 and the quill 54 from their openings in the hollow rail 4. For this purpose it is only necessary to disconnect the section 52 of the traverse-bar from its opposite section 51 or, if preferred, to remove the guide and former-arm 76 from the section 52, it being understood, of course, that the outrigger bracket 70 may be left attached to the main frame of the machine.

While the present machine is herein shown and described as embodied in a preferred form of construction, it is to be understood that modifications may be made in the structure and arrangement of its parts without departing from the spirit or scope of the invention. Therefore, without limiting myself in this respect, I claim:

1. In a winding machine, the combination of a trough-shaped hollow rail having aligned openings in its opposite sides, a bracket detachably mounted on said rail and carrying a plurality of bearings fitted to the openings in its opposite sides, a winding-spindle journaled in said bearings, a traverse-cam rotatably journaled on the bracket, driving-means connecting the winding-spindle and traverse-cam, a traverse-bar supported in bearings on the bracket and connected to be reciprocated from the cam, and a thread-guide carried on the traverse-bar, all the several parts specified being mounted on the bracket for removal from the rail as a unit, by withdrawing the bearings from the opening in one side of the rail and passing them through the opening in the opposite side thereof.

2. In a winding machine, the combination of a frame having a horizontal trough-shaped rail 135 formed with aligned openings in its opposite sides, a bracket detachably mounted on one side of the rail and having portions extending through the openings in both sides thereof, spaced bearings carried by the bracket at opposite sides of the 140 rail, a spindle journaled in said bearings, a thread-guide supported from the bracket for reciprocatory motion longitudinally of the spindle, a traverse-cam rotatably journaled on the bracket, and means connecting the cam to reciprocate the thread-guide, the parts of the mechanism specified being assembled on the bracket for removal from the rail as a unit by withdrawing the bracket portions from the opening in one 145 150

side of the rail and passing them through the opening in its opposite side.

3. A gang winding machine comprising a horizontally-extending bed provided with inverted trough-shaped rails extending longitudinally of its sides, said rails having openings therein in its opposite walls, brackets detachably fastened to the lateral walls of said rails, bearings on said brackets projecting through the openings in both walls of the rails, winding-spindles journaled in said bearings, traverse-cams rotatably journaled on the brackets, thread-guides slidably supported from the brackets for reciprocation longitudinally of the winding-spindles, and means connecting the cams to reciprocate the thread-guides.

4. In a gang winding machine, the combination of a frame comprising longitudinally-extending inverted trough-shaped rails arranged along the sides thereof, and formed with aligned openings in their opposite sides, brackets detachably fastened to the inner lateral walls of said rails, bearings carried on said brackets, winding-spindles journaled in said bearings to project through the outer side walls of the rails, traverse-cams rotatably journaled on the brackets, gearing connecting the winding-spindles and cams to be driven together, thread-guides slidably supported from the brackets for reciprocation longitudinally of the winding-spindles, and means connecting the traverse-cams to reciprocate the thread-guides.

5. In a gang winding machine, the combination of a frame comprising laterally-walled hollow rails extending longitudinally thereof and formed with openings in their sides, brackets detachably fastened to the lateral walls of the rails and provided with bearing-hubs fitted to the openings thereof, winding-spindles journaled in said bearing-hubs and projecting outwardly from the sides of the rails, thread-guides slidably supported from the brackets for reciprocation longitudinally of the winding-spindles, traverse-cams rotatably journaled on the brackets, means connecting the cams to reciprocate the thread-guides, gearing connecting the spindles to drive the cams, and belt-pulleys on the spindles located within the hollow rails to adapt them to be driven from a driving-belt extending longitudinally of the machine.

6. In a winding machine, the combination of a laterally walled casing having openings in its sides, a bracket detachably secured to the inner lateral wall of the casing and having hub-like portions extending through the openings thereof, a winding-spindle journaled in said bearings, bearing-sleeves supported from the bracket in parallel relation to the winding-spindle, a traverse-bar slidable in said sleeves, a thread-guide carried by said bar for reciprocation longitudinally of the winding-spindle, a traverse-cam rotatably journaled on the bracket, gearing connecting the cam for rotation with the winding-spindle, means connecting the cam to reciprocate the traverse-bar, and a belt-pulley on the winding-spindle for driving the latter.

7. A gang winding machine comprising a main frame having hollow rails extending horizontally along its sides and provided with openings in their lateral walls, end-members connecting the rails

to provide a box-like construction, brackets detachably secured to the inner side walls of the rails and provided with spaced bearing-hubs projecting through the openings thereof, winding-spindles journaled in said bearings, bearings carried on the bracket in parallel relation to the winding-spindle, traverse-bars reciprocable in the last-named bearings, thread-guides on the traverse-bars, stud-shafts projecting from the sides of the brackets parallel to the winding-spindle, traverse-cams journaled on said studs, gearing connecting the winding-spindles to drive the cams, means connecting the traverse-rods to be reciprocated from the cams, and belt-pulleys on the winding-spindles disposed between the spaced bearings thereof for engagement with belts passing longitudinally through the hollow rails of the machine.

8. A gang winding machine comprising a main frame constituted by opposite parallel side rails of walled construction, brackets detachably fastened to the inner walls of the side rails and provided with bearings projecting through the walls, winding-spindles journaled in said bearings and overhanging the side of the machine, other bearings supported on the brackets in parallel relation to the winding-spindles, traverse-rods slideable in said bearings, thread-guides carried on the traverse-rods, stud-shafts projecting laterally inward from the brackets, traverse-cams journaled on said stud-shafts, means connecting the cams to reciprocate the traverse-bars, gears on the winding-spindles and traverse-cams, change gearing meshing with the first-named gears to connect the cams to be rotated from the winding-spindles, and driving-pulleys on the spindles housed within the walls of the side rails to adapt them to be driven from belts extending longitudinally of said rails.

9. In a winding machine, the combination of a frame having a compartmented rail extending longitudinally thereof and provided with openings in its lateral walls, a bracket secured to the side of the rail and having hub-portions fitted to the openings in its walls, ball-bearings in said hub-portions, a spindle journaled in said bearings, a traverse-rod slideable through the walls of the rail in parallel relation to the winding-spindle, a traverse-cam journaled on the bracket, means connecting the cam to reciprocate the traverse-bar, and a thread-guide mounted on the traverse-bar for reciprocation therewith.

10. In a winding machine, the combination of a hollow side-rail having lateral walls with openings therein, a bracket abutting the side of the inner wall of said rail and detachably secured thereto, said bracket formed with bearing-hubs projecting through the openings in the walls of the rail, a winding-spindle journaled in said bearing-hubs and overhanging the side of the rail, bearings carried on the bracket in parallel relation to the winding-spindle, a traverse-bar slideable in said bearings and projecting outwardly in opposite relation to the winding-spindle, an out-board bearing for the outer end of the traverse-rod attached to the side of the rail, a cam journaled on the bracket, and means connecting the cam to reciprocate the traverse-bar.

EDWARD F. PARKS.
